UNITED STATES PATENT OFFICE.

ELISHA NOE, OF LARUE, KENTUCKY, ASSIGNOR OF ONE-HALF TO ELMIRA J. BENGE, OF BENGE, KENTUCKY.

COMBINED SAW-SET, JOINTER, AND WRENCH.

SPECIFICATION forming part of Letters Patent No. 626,767, dated June 13, 1899.

Application filed March 19, 1898. Serial No. 674,512. (No model.)

To all whom it may concern:

Be it known that I, ELISHA NOE, a citizen of the United States, residing at Larue, in the county of Clay and State of Kentucky, have 5 invented certain new and useful Improvements in a Combination Saw-Set, Jointer, and Wrench, of which the following is a full and complete specification, such as will enable those skilled in the art to which it appertains 10 to make and use the same.

This invention relates to saw-sets; and it has for its object to provide a simple and efficient saw-set device which will form a combination-tool capable of operation as a saw-set, jointer, or wrench.

15 The invention is fully disclosed in the following specification, of which the accompanying drawings form a part, in which the separate parts of my improvement are designated 20 by the same letters of reference in each of the views, and in which—

Figure 1 is a side view of the improved tool. Fig. 2 is a top edge view showing the saw in 25 position for setting. Fig. 3 is a bottom edge view showing the same in position for jointing, and Fig. 4 is a face view of the setting-die.

Referring to the drawings, A designates the 30 body of the device, which has a flat bottom edge or base a and a corresponding top surface or edge a' . The bottom or base edge a extends longitudinally with respect to the body A, while the top surface or edge a' extends part of the length of the body to an incline or shoulder a^2 , leading downwardly and 35 rearwardly to a reduced portion a^3 , which forms the rear end of the device and serves as the handle portion when the latter is used as a wrench. At the front end of the main portion of the body A is provided a flat face 40 or edge a^4 , while a similar flat edge a^5 is provided at the end of the narrow or reduced rear portion a^3 . The wrench is formed by a jaw B, operating with respect to the end a^4 (which end of the body thus forms one of the jaws 45 of the wrench) and carried upon a stem b, extending longitudinally through the body A at the base portion thereof, said stem being accommodated in a corresponding opening in the body A and being provided with a projecting threaded rear end b' , which carries a

thumb-nut c, adapted to bear against the end a^5 of the reduced rear end portion a^3 of the body.

At the vertex of the angle formed by the top edge a' and the incline a^2 is provided a 55 plate d, against which the tooth lies in the operation of setting the saw. This plate is preferably formed of hardened steel and is approximately V-shaped, and it may be secured in a corresponding recess provided in the body 60 A at the vertex of said angle.

At the junction of the base of the incline a^2 and the front end of the reduced rear portion a^3 is pivotally mounted, as at e, a set-arm F, adapted to project upwardly with relation to the incline a^2 and provided with a head f, suitably beveled, as at f', and adapted to operate with relation to the plate d. The set is regulated by a screw g, upon which the saw-plate rests in operation, it being simply 70 necessary to raise or lower the screw.

The operation and advantages of my invention will be readily understood by those skilled in the art to which it appertains.

In the operation of setting a saw the device 75 is rested upon its bottom edge or base a and the saw is placed upon the device with its tooth under the free-headed end of the pivoted set-arm F, when the latter is struck with a hammer. In the operation of jointing the saw 80 with my improved device the sharpening-file is placed in position within the wrench between the wrench-jaw B and the jaw formed by the end a^4 of the body A, and the wrench device is tightened up by operation of the 85 set-nut c. In the operation of jointing the set-arm F can be thrown back upon its pivot e, so that it will fold down into the position shown in dotted lines in Fig. 1, (as it would otherwise form an obstruction,) and the screw 90 g is also removed. The saw can be set up on handles or laid upon a plank, and then the jointer is placed on, and inasmuch as the slide that slips along the saw-plate is straight and the wrench holds the file in a perfectly 95 or exactly square relative position the device will operate to leave the teeth in a perfectly level condition.

The device is adapted for effective operation in the setting or jointing of any kind of 100

a saw, and it is also capable of effective use as a wrench for general purposes. It will also be noted that as the set-arm F fits upon the tooth with the portion f' of its head f, said portion being approximately V-shaped, the operation is greatly facilitated and rendered more efficient.

Having fully described my invention, I claim as new and desire to secure by Letters 10 Patent—

1. In a device of the class described, the combination with the body having a reduced portion, of a set-arm pivotally connected with said reduced portion, an angular plate secured to said body and slanting upwardly 15 from said reduced portion, said reduced portion forming a handle, the opposite end of the body forming a wrench-head, and a wrench-jaw operating with respect to said wrench-head and carried by a stem projecting through 20 said body, substantially as and for the purpose set forth.

2. In a device of the class described, the combination with the body forming at one end 25 a wrench-head, of a wrench-jaw operating with respect to said wrench-head and carried by a stem projecting through said body and a set-arm pivotally secured to said body, substantially as and for the purpose set forth.

3. In a device of the class described, the combination with the body forming at one end a wrench-head, of a wrench-jaw operating 35 with respect to said wrench-head and carried by a stem projecting through said body, a set-arm pivotally secured to said body, means secured to said body for adjusting the saw to be set and means for adjusting said wrench-jaw, substantially as and for the purpose set forth.

4. A combination tool or device of the class

described, comprising the body having the main portion provided with a flat top edge and with an end operating as a wrench-jaw and having the reduced portion in rear of said main portion, a wrench-jaw operating 45 with respect to said end and carried upon a stem mounted in the body, means for adjusting said wrench-jaw, and a set-arm pivotally mounted at the base of the rear end of the larger main portion of the body and having 50 a head adapted to operate with respect to the top edge of the same, said set-arm being adapted to fold down upon the reduced portion, substantially as and for the purpose set forth.

5. The herein-described combination tool or device, comprising the body having the longitudinal flat or straight base edge and embodying the enlarged portion provided with the flat top edge and the reduced rear portion, the front end of said body at its enlarged portion being adapted to form a wrench-jaw, a wrench-jaw operating with respect to said end and carried upon a stem projecting through the body, set devices upon said stem 65 for adjusting the wrench, and the set-arm pivotally mounted at the base of the rear end of the larger portion of the body and having a head operating with respect to the top edge of the same, substantially as and for the purpose set forth.

In testimony that I claim the foregoing as my invention I have signed my name, in presence of the subscribing witnesses, this 14th day of March, 1898.

ELISHA NOE.
